CLAIM

The ornamental design for a bait bucket, as shown.

DESCRIPTION

FIG. 1 is a perspective view of a bait bucket of the present invention;

FIG. 2 is similar to that of FIG. 1 but with a top portion of the invention separated from and positioned above a lower portion of the invention that includes a drawer that is partially pulled out for purposes of illustration; FIG. 3 is a side view in elevation of the invention of FIG. 1;

FIG. 4 is a plan view of the invention of FIG. 1; and FIG. 5 is a bottom view of the invention of FIG. 1.
